DESIGN FOR A ROCKET MOTOR

John Carver Baker, Pasadena, Calif., assignor to
Aerojet Engineering Corporation, Pasadena,
Calif., a corporation of Delaware

Application September 21, 1943, Serial No. 111,172

Term of patent 14 years

(Cl. D71—1)

To all whom it may concern:

Be it known that I, John Carver Baker, a citizen of the United States, residing at 419 South Meridian Avenue, Pasadena, in the county of Los Angeles and State of California, have invented a new, original, and ornamental Design for a Rocket Motor, of which the following is a specification, reference being had to the accompanying drawing, forming a part thereof.

Fig. 1 is an isometric view of a rocket motor showing my new design;

Fig. 2 is a side elevational view of the rocket motor; and

Fig. 3 is an end view of the motor as viewed from the tail end.

The characteristic features of my design are shown in full lines in the drawing.

I claim:

The ornamental design for a rocket motor, substantially as shown and described.

JOHN CARVER BAKER.
